BY *Murphy*
ATTORNEY

UNITED STATES PATENT OFFICE.

HUGH JOHNSTON SLOAN, OF WAYNESVILLE, NORTH CAROLINA.

DEVICE FOR FACILITATING THE REMOVAL OF SHACKLE BOLTS.

Application filed March 17, 1927. Serial No. 176,154.

This invention pertains to a device for facilitating the removal of shackle bolts from automobiles and similar vehicles, and has for its object the provision of such a device which is steady in operation, easily constructed, and which is inexpensive to manufacture.

In automobiles, for example, at times, there may be wear on the shackle bolt connecting the springs and beams with the body, so that removal of these bolts becomes desirable for replacement, or for repairing. The device of the present invention facilitates the removal of these bolts when such is desired, and does so in an expeditious manner and with a minimum of trouble.

The construction of the device will be apparent from the accompanying drawings, in which—

20 Figure 1 is a vertical section taken through the frame member and connected spring of an automobile, showing in elevation, the device of the present invention applied thereto.

25 Fig. 2 is a perspective view of the device itself, and

Fig. 3 is a perspective view showing the device attached to the body and spring, as in Fig. 1, but being taken from the side instead of from the rear, as in the case of 30 Fig. 1.

Referring more particularly to the drawings, the device itself consists of a standard 1 which is formed with threads along the 35 greater part of its length, and carries an adjustable clamping device of U-shape in cross section represented generally at 6, which device is slidable along the standard 1 by reason of its threaded connection therewith. One end of the standard is flattened and formed as an eye to which is secured a 40 fixed clamping member 2, provided with a movable jaw 4, which is operated upon screw threads by the turning of member 3. Threadedly engaging the standard 1 is the 45 nut 5, which is adapted to secure the clamp 6 in any required position.

The clamping member represented generally at 6, comprises two clamping screws 50 7 and 7' passing through the support 6, and also comprises a lug 12, which is secured to the support 6 as shown in Fig. 1. Movement of the clamp 6 out of engagement with the

standard 1 is prevented by a pin 11, which passes through an opening in the standard 55 for this purpose.

In operation the clamp 2 is placed in engagement with the frame of the vehicle and the movable jaw 4 moved up against the side of said body, and is secured in position by the manipulation of the member 3. Clamp 6 is moved in position for registering with the spring 8, and is secured in position by the lock nut 5. Members 7 and 7', which may be called clamping screws are then operated until they come into contact with the spring 8, as shown in Figures 1 and 3 and are clamped tightly upon the spring. The spring further contacts with the lug 12 as shown in Fig. 1, this lug preventing any 70 distortion of the spring, and also facilitating the holding of the clamping member 6 in rigid position. The device being thus secured both to the body of the machine and to the spring, pressure is exerted upon the 75 device, which relieves the tension of the spring upon the bolts 9 so that the bolts 9 may be readily removed whenever desired.

It is to be noted that the above description is illustrative of the device, variations 80 therefrom being permissible within the scope of the appended claims.

I claim:—

1. An instrument of the class described comprising a standard, a clamping member 85 fixed in position longitudinally thereon and laterally adjustable relatively thereto, a second clamping member mounted on the standard for adjustment longitudinally thereof, and means operable to secure the 90 second clamping member in adjusted position on the standard.

2. A device of the character described comprising a standard, a clamping member fixed in position on the standard, a second 95 clamping member adjustable longitudinally along said standard, and relatively to the first clamping member, and means for setting the movable clamping member in position upon the standard.

3. A device as set forth in claim 2 in which the second clamping member includes oppositely directed and operating screw members adapted to move toward each other.

4. A device to facilitate the removal of

- shackle bolts on vehicles which comprises a standard having thereon clamping means adapted to fit the frame of the chassis, a second and relatively movable clamping means adapted to grip the spring of the vehicle and mounted for adjustment longitudinally of the standard, and means engaging with said standard for securing the said second clamping means in adjusted position.
10. 5. A device as set forth in claim 4 in which the movable clamping member comprises a clamp screw support and oppositely disposed clamping screws extending through the support.
15. 6. A device as set forth in claim 4 in which the means for securing the movable

clamping member in adjusted position comprises a nut threadedly engaging the standard.

7. A device of the character described 20 having in combination a threaded standard, and separate frame and spring clamping members mounted on and laterally offset from said standard, one of said clamping means being fixed in position longitudinally 25 of the standard and adjustable laterally with respect thereto, and the other of said clamping members being adjustable longitudinally of the standard with means to secure the same in adjusted position.

HUGH JOHNSTON SLOAN.
